COMPOSITE BOW AND HAND GRIP FOR THE SAME

Roy A. Huntley, 1108 9th Ave., Seattle, Wash.
Filed Nov. 13, 1962, Ser. No. 237,005
4 Claims. (Cl. 124—24)

This present invention relates to the general field of making resilient bows of the type employed for the discharge of arrows. More specifically, this invention relates to a built-up composite style of bow and employs a handle having its axis at right angles to the axis of the bow proper which insures a more uniform handling of the bow from shot to shot and permits improved delivery of the arrow as it passes the bow during its projection.

In the field of archery a large number of bow and arrow arrangements have been developed using a wide variety of materials. In my present composite style bow I prefer to employ a backing strip on the outer surface of the bow, and on the inner surface, facing the Bowman, to employ the principal resilient member extending substantially throughout the length of the bow, which may be made of suitable metal as steel, or in some instances, because of the current wide development of plastic materials, certain of these may be used. The thickness of this resilient and principal projection member of the bow will vary in compliance with the physical resilience or elasticity of the material used. A satisfactory measure for the comparison of the different materials is Young's Modulus of Elasticity. This covers the ratio of stress to strain or the rate of change of strain below the proportional limit. Another factor allied to elasticity is resilience, which for this present purpose is defined as the energy stored in a body when the stress in the bow projection material is increased. In bow making the stress varies from the amount applied to the material when the bow is strung to the amount which occurs at its peak when the bow is fully drawn, as in the discharge of an arrow.

Further consideration in making a bow for accurate, effective use is the necessity of applying a handle to the bow in a manner that will insure a uniform holding of the bow for each successive discharge of arrows. Bows are generally used for two purposes, one for archery practice and finally archery tournaments, and secondly in the sports field for hunting game, ranging from small game or varmints to all of our soft skinned animals. Particularly in the hunting field it is very desirable that the bow be reasonably short so that it can be practically used with the longitudinal axis of the bow substantially horizontal. In my present composite bow I provide a handle which insures a comfortable holding of the bow when in the preferred hunting position, which is the horizontal position. By employing a separate handle which is attached to the bow by suitable means, it is possible to provide for uniform movement of the arrow past the bow itself, a result which is difficult of uniform achievement with the ordinary long bow normally used in the vertical position.

A principal object of this present invention therefore is to provide a composite bow structure which is readily adaptable to bows of various drawing weight and which admits the use of various types of material other than wood, which have been created by our intense technological development, particularly during the last one or two decades.

A further object of this invention is to provide a bow of such a structure that it can be made in a reduced overall length so as to adapt it to the horizontal holding position so generally used by hunters.

2

A further object of this invention is to provide in a composite bow a reinforced tip-nock recurvature spring end.

5 A further object of this present invention is to provide a bow handle having a grip trip which will insure a uniform handling of the bow under various shooting conditions.

10 Further objects, advantages and capabilities will be apparent from the disclosure in the drawings or may be comprehended or are inherent in the device.

In the drawings:

15 FIGURE 1 is a top plan view of a bow made after the teachings of this present invention, showing the bow as strung and illustrating, in dashed lines, one side of the handle, the normal position of the bow ends when the bow is unstrung.

20 FIGURE 2 is a side elevation of the bow of FIGURE 1 with a portion of the same broken away.

25 FIGURE 3 is a cross-sectional view taken along the line 3—3 of FIGURE 2.

FIGURE 4 is a top plan view, on an increased scale, of the recurvature nock tip, the same construction being employed at both ends of the bow.

30 FIGURE 5 is a cross-sectional view, on an increased scale, along the line 5—5 of FIGURE 2.

35 FIGURE 6 is a perspective view, on an increased scale, of the handle used in association with this bow, the same being shown in perspective to better illustrate certain features.

30 FIGURE 7 is a fragmentary view showing, in side elevation, the handle seating portion of the bow.

Referring to the drawings, throughout which like reference characters indicate like parts, the numeral 10 designates the body strip which extends throughout the 40 length of the bow and is of substantial thickness that will vary with the arrow casting force desired. In the proportions shown in FIGURE 3 this material is indicated as duralumin. As will be noted, especially in FIGURE 4, the recurvature 12 of the bow is formed by carrying this 45 principal back bone member through the nock portion. Overlaying the outside of the principal strip 10 is a thinner backing portion 14. This backing portion is preferably a relatively thin strip of a high grade resilient steel of the order of SAE 1085 or 9260 which are quite satisfactory for this purpose, a preferred thickness ranging from 18 to 14 gauge. It is to be noted that strip 14 extends substantially from one end of the bow to the other as shown in FIGURE 1. The extreme end of strip 14, at each end of the bow, is secured by an overlapping relieved portion 15 formed in nock member 20. Member 20 is preferably made of the same material as strip 10 and is fastened in place by compression means as by being through bolted by bolt 21 to strip 10. It will be noted particularly in FIGURES 2 and 4 that the ends of strip 10 and member 20 are bifurcated at 22 to form what in this bow is the nock in which the bow string 24 is operationally secured when the bow is strung. Suitable knots, as 26, are made in each end of the bow string. The back side of the recurvature ends are grooved at 13 to retain the bow string around the ends as the bow is drawn.

Referring now to FIGURE 7, the preferred structure is illustrated in the present instance as a top plan view though taken from the showing of FIGURE 1, but on an increased scale and with the handle removed. To give added strength, a third or handle reinforcing strip 28 is provided. A satisfactory reinforcing strip 28 is approximately one fourth of the total length of the bow and the same is centered on the center of the bow. Completing the handle reinforcement 29 is a base member 30 having a relatively thick grip portion at its center and reduced thickness portions as 31 at its opposite ends. As will be noted in FIGURE 7, the four pieces making up the lami-

nated main body of the bow where the handle is attached are secured together in operational relationship by the through bolts 32.

Referring to FIGURES 5 and 6, the handle or hand grip portion of the bow 34 is shown in FIGURE 5 in operational relationship wherein it is secured to the center portion of the bow, after the showings in FIGURES 1 and 2 and in FIGURE 6 where the same is shown by itself for a more clear understanding. A preferred material for the main part of the handle indicated at 34 is any of the moldable plastic materials that can be used in all kinds of weather without any change and are very durable. The handle consists of a hand grip portion proper 35, having the finger gauge 36 secured thereto on its forward edge and this is preferably held in place by suitable means as the screw 37 so that this member can be individually adjusted to the size of the user's hand. As generally used, this is employed below the little finger of the left hand of a right handed person. The upper portion of handle 34 is provided with two guide and rest members 38 and 40. Members 38 and 40 are used as rests for the index finger and thumb of the hand holding the bow and complete the gripping of the bow. This additional support resists any tendency for the drawing of the bow to overturn the bow and handle 35. The material between guides 38 and 40 is depressed after the showing of FIGURE 2, to provide the arrow guide valley 42. An angled seat 44 is provided, making use of the under side of members 38 and 40. These are connected by a planar surface 46 providing an angled seat which insures the proper positioning of the various laminates of the bow in the horizontal and vertical planes, particularly if one of the bolts should happen to loosen in use. A through bolt 48 is provided, passing through hole 49, which in turn passes entirely through the handle portion as is probably best illustrated in FIGURE 7. Completing the grip portion is a preferably metal guide member 50, which overhangs the handle to the rear and is secured to handle member 35 by screw 52 and by the sides 54 of the handle portion which enclose the side walls of the guide. Guide member 50 has been found desirable because of the fact that the bow itself is intended for normal use in the horizontal position, as distinct from the vertical position employed with the ordinary long bow.

The various laminates shown in FIGURE 7 are additionally secured together by a plurality of suitable encircling bands 60. To complete the bow and insure that all the laminates will remain in their operational positions I have provided a cover 56 of material such as leather, raw hide or reinforced plastic material, and have shown the same as secured along its center line by seam 58 especially protecting the steel member 14 from the elements and providing a neat organization of all the parts.

It is believed that it will be clearly apparent from the above description and the disclosure in the drawings that the invention comprehends a novel construction of composite bow and hand grip for the same.

Having thus described my invention, I claim:

1. A composite bow and hand grip, comprising: a body strip of metal extending throughout the length of the bow; recurvature ends, grooves on their back side formed in the ends of the body strip; nock members fitting the outside curvature of said recurvature ends and bifurcated to provide nock slots to engage the ends of an end knotted bow string; compression means to secure said nock members to said body strip; a backing strip of metal overlaying the outside of said body strip and extending substantially the length of the same; said backing strip having its ends secured by said nock members; a metal reinforcing strip extending substantially one eighth of the length of said bow on each side of its center; a base member overlaying said reinforcing strip on its outside surface and having a relatively thick grip portion and end portions of reduced thickness; compression means for securing said strips and said base member in close operational relationship and a handle secured at the longitudinal center of said bow

and at right angles to the plane of the bow and bowstring when the bow is drawn.

2. A composite bow and hand grip, comprising: a body strip of metal, of substantial thickness, extending throughout the length of the bow; nock members fitting the outside end surfaces of the ends of the bow and bifurcated to provide nock slots to engage the ends of an end knotted bow string; compression means to secure said nock members to said body strip; a backing strip of relatively thin metal strip overlaying the outside of said body strip and extending substantially the length of the same; said backing strip having its ends secured by said nock members; a metal reinforcing strip extending substantially one eighth of the length of said bow on each side of its center; a base member overlaying said reinforcing strip on its outside surface and having a relatively thick grip portion and end portions of reduced thickness; compression means for securing said strips and said base member in close operational relationship and a handle secured at the longitudinal center of said bow and at right angles to the plane of the bow and bowstring when the bow is drawn.

3. A composite bow, comprising: a body strip of metal of substantial thickness, extending throughout the length of the bow; recurvature ends, grooves on their back side formed in the ends of the body strip; nock members fitting the outside curvature of said recurvature ends and bifurcated to provide nock slots to engage the ends of an end knotted bow string; compression means to secure said nock members to said body strip; a backing strip of relatively thin strip metal overlaying the outside of said body strip and extending substantially the length of the same; said backing strip having its ends secured by suitable means; a metal reinforcing strip extending substantially one-eighth of the length of said bow on each side of its center; a base member overlaying said reinforcing strip on its outside surface and having a relatively thick grip portion and end portions of reduced thickness; compression means for securing said strips and said base member in close operational relationship and a handle provided at the longitudinal center of said bow consisting of the said strips and said base member.

4. A composite bow and hand grip, comprising: a body strip of metal extending throughout the length of the bow; recurvature ends, grooves on their back side formed in the ends of the body strip; nock members fitting the outside curvature of said recurvature ends and bifurcated to provide nock slots to engage the ends of an end knotted bow string; compression means to secure said nock members to said body strip; a backing strip of metal overlaying the outside of said body strip and extending substantially the length of the same; said backing strip having its ends secured by said nock members; a metal reinforcing strip extending substantially one-eighth of the length of said bow on each side of its center; a base member overlaying said reinforcing strip on its outside surface and having a relatively thick grip portion and end portions of reduced thickness; compression means for securing said strips and said base member in close relationship; a handle secured at the longitudinal center of said bow and at right angles to the plane of the bow and bowstring when the bow is drawn and said handle having a hand grip portion with a detachable finger gauge secured on its forward edge in predetermined position, spaced apart finger and thumb rests rising above the plane of the strung bow and having an arrow guide valley between them and a metal guide member overhanging said handle, sloping upwardly to the handle and secured thereto.
